UNITED STATES PATENT OFFICE.

EARL H. BISHOP, OF BUTLER, PENNSYLVANIA.

END CONNECTER FOR CHAINS.

Application filed February 14, 1925. Serial No. 9,096.

The present invention relates to means for connecting the ends of chains, and more particularly the ends of the side chains of anti-skid chains for automobiles.

5 In the accompanying drawings:—

Figure 1 is a side elevation illustrating a preferred embodiment of my invention applied in operative relation to the ends of a chain;

10 Figure 2 is a corresponding plan view, and

Figure 3 illustrates the manner in which the connector is engaged with the free end of the chain.

15 The connector is made in one piece and is adapted to be stamped out of relatively thin metal of substantially uniform thickness. The body portion 2 of the connector has a hole through one end portion thereof to receive a pintle 3. This end of the connector is adapted to be received between the usual loop portions 4 formed at one end of a chain link and to have the pintle pass through said loop portions and said hole.

20 Extending from the opposite end of the body portion 2 is a projection 5, the lower edge 6 of which is adapted to engage the upwardly extending ends 7 of the loop portions 4 of the link when the connector is engaged therewith, as illustrated in Figures 1 and 2.

25 The body portion 2 has a slot 8 intermediate its ends to receive the cross-bar 9 at the end of a chain link. This slot extends from the upper edge of the connector obliquely downwardly towards the free end thereof. The slot is deep enough so that its lower edge is substantially in the same straight line with the center of the hole which receives the pintle 3 and the lower edge 6 of the projection 5. With this construction, when the ends of a chain are fastened together by the connector, as illustrated in the drawings, and tension is applied thereto, the pull is exerted in a substantially straight line with little upward thrust on the projection 5.

30 The manner of engaging the connector with a link at the free end of a chain is illustrated in Figure 3. It will be noted that the

connector is so proportioned that the link must assume a position substantially at right angles to the longitudinal axis of the connector before it can be engaged with or disengaged from the slot 8. The width of the connector, measured along a line *a*—*b* extending through the center of the upper end of the slot, is slightly less than the length of the opening in the link measured from the cross-bar 9 to the ends 7 of the loop portions 4. The body portion gradually tapers in width from the line *a*—*b* to the free end of the body portion. The edge 10 of the body portion at the free end thereof makes an abrupt angle with the lower edge 11 of said body portion. It will be apparent that when the chain becomes slack the link 12 cannot back out of engagement with the slot 8 because the ends 7 of the link will engage the edge 10 before the cross-bar 9 reaches the upper end of the slot 8. This is illustrated by the chain line position of the link 12 illustrated in Figure 3. In other words, the distance between the upper end *c* of the slot 8 and the point of intersection 13 of the end edge 10 with the lower edge 11 of the body portion is substantially greater than the length of the opening in the link, so that the link 12 must be swung out of engagement with the end edge 10 and assume a position at substantially right angles to the longitudinal axis of the connector before it can be disengaged from the slot 8. Under normal operating conditions it could not assume such a position accidentally.

35 While I have shown and described a preferred embodiment of my invention, it will be understood that the invention is not limited to the details of construction shown but that it may be otherwise embodied within the scope of the appended claim.

I claim:

40 A connector for tire chain ends, comprising an elongated body member having convex side edges, one of which is continuously convexed throughout its length, the said body having a diagonally disposed slot 45 extending inwardly from the other edge intermediate its ends partway across the width of the body, the said continuously convexed 50

side of the body being shorter than the other side whereby an overhanging tail portion is provided at one end of the body, said convexed edges of the body serving to reduce the area of the body which may contact with a tire and serve to reduce the danger of the body injuring the tire with which it con-

tacts, the centers of curvature for the convexed surfaces of the body being out of alignment whereby the central portion of the body is of substantially uniform thickness.

In testimony whereof I have hereunto set my hand.

EARL H. BISHOP.
